Specification of Letters Patent.

Patented Dec. 5, 1916.

Application filed May 10, 1915. Serial No. 27,093.

To all whom it may concern:

Be it known that I, HOWARD D. COLMAN, a citizen of the United States, residing at Rockford, in the county of Winnebago and 5 State of Illinois, have invented certain new and useful Improvements in Warping Apparatus, of which the following is a specification.

This invention relates to apparatus for 10 winding yarn upon a warp beam from individual yarn masses which rotate to deliver the yarn. The individual yarn masses may be of various forms, as, for example, spools or cylindrical cheeses. As ordinarily practiced, such warping is conducted at a yarn 15 speed of about sixty yards a minute. If a much greater speed than this is attempted, the cheeses or spools will ordinarily coast so much farther than the beam at the time 20 of each stop that the rise-roll or fall-roll of the warper is unable to take up the slack. This difficulty may be overcome by putting a fly wheel on the warper so that the beam 25 will coast farther than the farthest-coasting cheese, but this would cause the warper to run so long after a thread breaks that the end of the broken thread would be wound under too far, and the warper tender would either not be able to find the lost end at all, 30 or, if found, she would in most cases probably not be able to tie it up without introducing a crossed thread. In ordinary practice, when the velocity is about sixty yards a minute, the spools will coast perhaps three 35 or four yards, and the beam about a yard or a yard and a half less, the difference being taken up by the slack-take-up roll of the warper. If the velocity is to be increased to several times the usual speed, the amount of 40 coasting will become very great, since the coasting increases in proportion to the square of the velocity, but on account of the difficulty in finding and properly tying up the end of the broken thread, it is impracticable to permit of a considerable increase 45 in the amount of coasting of the beam. It is also impracticable to allow any considerable difference between the amount of coasting of the beam and the amount of coasting 50 of the spools, since the amount of slack to be taken up by the slack-take-up roll cannot be materially increased on account of limitations of space.

One of the objects of this invention is to

provide a warping apparatus by means of 55 which warping may be done at a very high speed as compared with ordinary warpers, say a speed several times the ordinary speed. In the present embodiment, this object is attained by providing an individual brake 60 for each cheese, and by providing a beam brake which is sufficiently powerful so as to prevent the beam from coasting so far as to cause difficulty in finding and tying up the broken end, the beam brake being so 65 proportioned to the cheese brakes that the beam always coasts a little farther than the cheeses would coast if the cheeses were disconnected from the beam at the moment of 70 application of the cheese brakes, or in other words, the beam while coasting always causes the cheeses to revolve a little longer than they would if disconnected from the beam. Thus the cheeses and the beam are 75 brought to rest without either slackening or severing the strands extending between the cheeses and the beam, slight differences in the extent of coasting of the various cheeses merely producing differences in the tension 80 of the individual strands. Each cheese brake is of such character as to cause a large cheese to be stopped nearly as quickly as a small one, and each cheese brake is also of practically constant efficiency.

In the accompanying drawings, Figure 1 85 is a fragmental side elevation of a warping apparatus embodying the features of my invention, the parts being in running position. Fig. 1^a is a fragmental view of one of the removable creel-sections. Fig. 2 is a side 90 elevation of the creel, most of the brakes and the creel-sections being omitted for the sake of clearness. Fig. 3 is a plan view of the creel, with the parts in running position, and the machine at rest. Fig. 4 is a fragmental inner side view of one of the creel frames. Fig. 5 is a fragmental horizontal 95 sectional view of the creel. Fig. 6 is a view showing a brake as applied to a cheese. Fig. 7 illustrates the connection between the 100 cheese-brake members and their supporting shafts. Fig. 8 is a fragmental vertical sectional view of one of the creel frames, showing the brakes as released. Fig. 9 shows a brake as applied to a cheese. Fig. 10 is a 105 view of the upper portion of a creel frame, showing means for supporting and braking extra cheeses. Fig. 11 is a side elevation

illustrating the brake-operating mechanism, the brakes having been restored to initial or inoperative position, and the apparatus being at rest. Fig. 12 is a fragmental view showing the parts in process of being restored to initial position. Fig. 13 is a view from the side opposite to that seen in Fig. 11. Fig. 14 illustrates the means for locking the brakes in initial position. Fig. 15 shows a means for preventing the warper from being operated until the brakes have been restored to initial position. Fig. 16 illustrates certain parts in the position assumed when the warper is running. Fig. 17 is a plan view of the brake-operating mechanism.

The present embodiment of the invention comprises a creel and a warper, the warper being of common construction save that the beam brake has been replaced with one that is sufficiently powerful for the attainment of the desired results.

In Fig. 1, B indicates a section beam. Suitable means (not herein shown) may be employed to prevent the formation of an eccentric yarn mass on the beam. D are the drop wires for detecting thread breakages, and F the usual slack-take-up roll resting upon the sheet of warp threads. As herein-before suggested, the threads are kept taut at all times by the coaction of the cheese brakes and the beam brake and without the assistance of the fall roll F, the latter being retained in the warper for the purpose of preventing slack in case of a sudden accidental decrease in the speed of the beam, for the purpose of indicating to the operative when the beam brake requires adjustment, and to prevent slack when the beam comes to rest after having been revolved slowly preparatory to going onto higher speed.

While the invention in its broadest aspect is applicable to the unwinding of various forms of yarn masses, it is herein illustrated as embodied in a machine for unwinding yarn masses in the form of cylindrical cheeses α . Each cheese consists of yarn cross-wound upon a cheese tube b (Fig. 1^a). In the illustrative form herein shown, the cheese tube consists of two cylindrical sheet-metal sections b^1 and b^2 rigidly secured together, each of said sections having an annular end wall b^3 . In each of the end walls b^3 is a central opening surrounded by an inturned flange b^4 . A sleeve b^5 extends centrally of and within the sections b^1 and b^2 and surrounds the flanges b^4 .

In the creel the cheeses are rotatably supported upon spindles 1, four cheeses, in the present embodiment being carried by each spindle. The cheese tubes are not mounted directly upon the spindle, but are carried by rollers 2 which are rotatably supported upon the spindle. In the construction herein shown, each roller is formed of sheet metal 65 and comprises annular bearing flanges 2^a

which fit rotatably upon the spindle. The opposite ends of the roller are slightly reduced in diameter to provide surfaces 2^b for supporting the bearing flanges b^4 of the cheese tubes. By reason of such reduction in diameter the roller has a generally crowning form which prevents the cheese from moving laterally into contact with the adjacent cheeses when revolving in the creel. The greatest diameter of the roller 2 is sufficiently less than the smallest internal diameter of the cheese tube so that the latter may be readily slipped on and off the roller by the operative.

The rollers 2 are prevented from being displaced endwise by means of sleeves 3 which are rotatably mounted upon the spindle 1 between the rollers. The ends of the rollers are countersunk so as to overhang the sleeves 3, and said sleeves are provided near their ends with annular flanges 3^a which prevent yarn from getting between the ends of the rollers 2 and sleeves 3. In case some yarn should become wound around one of the sleeves 3, the yarn may be readily unwound therefrom, as the sleeve will rotate freely as the yarn is withdrawn.

To lubricate the spindles 1, a small quantity of oil α is placed in each roller 2 before the roller is placed upon the spindle in the operation of assembling the parts. The quantity of oil is preferably so small that the level of the oil never touches the spindle whether the spindle is in horizontal or vertical position. When the spindle is in the creel and the rollers 2 are revolving, some of the oil is carried up onto the outer surface of the flanges 2^a. When the spindle is subsequently placed in vertical position, some of the oil on said flanges flows onto the spindle.

In the construction herein illustrated, the spindles 1 are arranged in groups of three, each group being fixed to a base 4 (Figs. 1^a and 8). Upon the end of each spindle 110 is mounted a cap 5. Spacer sleeves 3 are provided to space the rollers from the cap and the base. Each base 4 with its row of spindles 1 will hereinafter be termed a trident. The tridents are adapted to be used at the winder as a receptacle or a support for the cheeses when the latter are removed from the winder. When in use at the winder, the tridents rest upon the bases 4 with the spindles 1 in upright position. When in such position the cheese tubes b on a given spindle rest upon one another. When the tridents are in use in the creel, the spindles occupy a horizontal position, the cheese tubes being out of contact with each other.

The framework of the creel may be of any suitable character. As herein shown, it consists of two upright frames 6 and 7 (Fig. 3) which are adjacent each other at

one end and separated from each other at the opposite end so as to constitute a V-shape structure. The frames 6 and 7 are suitably braced and connected together. In 5 the particular embodiment selected for illustration, each of the frames 6 and 7 is composed of six bays, each adapted to support three tridents arranged one above the other. The tridents are insertable and removable 10 through the outer sides of the frames 6 and 7. At the left-hand side of each bay are sockets 8 (Figs. 3, 5 and 8), each intended to receive one end of the base 4 of a trident. At the front end of each socket 8 15 is a projection 9 on which the operative may momentarily rest the base of the trident while placing the trident in the creel-frame. At the right-hand side of the bay are sockets 10 (Figs. 1 and 5) to receive the caps 5. For each socket 10 there is a guide flange 11 to assist the operative in setting the trident in place. Each bay is provided on its outer side with a gate 12 hinged at 13. (See Figs. 3, 8 and 10.) The gate is 20 held shut by means of a projection 14 (Fig. 10) on the gate adapted to lie in a recess 15 on a locking member 16 fixed to the creel-frame. Each gate is provided with guide rods 17 for guiding the threads from the 25 cheeses to the warper.

The mounting of a plurality of cheeses upon each spindle conduces to a very compact arrangement of the cheeses in the creel, as will be apparent from Fig. 2.

35 The winder operatives place the cheeses upon the tridents in such a manner that when the tridents are set in the creel-frame the yarn shall unwind from the upper portions of the cheeses. As the tridents may 40 be set in the creel-frame with either end up, the warper tender can place the tridents without giving any attention to the matter of seeing that the yarn unwinds from the upper part of the cheeses. After placing 45 the tridents in the creel-frame, the warper tender spaces the cheeses properly upon the spindles, so that each cheese rests upon its roller 2.

It will be seen that the creel comprising 50 as it does tridents each of which is supplied with twelve cheeses at the winder, may be filled and emptied very quickly, and with a minimum of handling of the cheeses.

To keep the yarn from some of the lower 55 cheeses out of contact with the next higher cheeses, certain of the guide rods 17 are provided with thread-guiding notches 18 (Fig. 8).

60 Referring now to the cheese brakes: At any given stop each cheese coasts about the same amount as all the other cheeses, because the cheeses are all approximately the same size, and because of the character of the braking surfaces. One of these surfaces is 65 the surface of the yarn mass and the other

is a polished metal plate. The rubbing of the yarn against the plate in stopping keeps the plate bright so that the surface condition of the plate remains very nearly constant. As stated, the other braking surface 70 is the yarn, and as a new surface is constantly being presented to the brake (owing to the unwinding of the yarn) there is no change in the characteristics of this surface due to wear, and other changes due to such causes as temperature and humidity affect 75 all of the cheeses alike.

19 indicates the polished metal plate comprised in each cheese brake. The plate is 80 preferably curved so as to present a convex surface to the yarn mass and is arranged to bear against the middle of the periphery of the cheese in order that when the plate is pressed against the cheese the latter shall not be tilted so as to bring its tube 6 into 85 contact with an adjacent tube.

The brake plates 19 are pivotally mounted upon rock shafts 20 which are supported upon the inner side of the creel-frame.

21 are individual torsion springs for the 90 brake plates, one end of each spring being secured to the rock shaft and the other end to the brake plate. The springs 21 normally hold the brake plates 19 in contact with stop arms 22 fixed to the shafts 20, each 95 arm having two lugs that overlie the adjacent brake plates. When the cheeses are to be braked, all of the shafts 20 are turned (by means to be later described) to swing the brake plates 19 against the cheeses. The 100 rock shafts 20 are connected together for simultaneous movement by means of crank arms 23 and vertical connecting rods 24 (Figs. 3 and 8).

In the upper portion of the creel is supported a horizontal rock shaft 25 having arms 26 fixed upon its ends. These arms are connected to two of the crank arms 23 by means of links 27 (Figs. 8 and 13). A tension spring 28 anchored at one end to 110 the creel framework and connected at its other end to an arm 29 which is rigid with the rock shaft 25, tends to turn said shaft in the direction to swing the brake plates 19 against the cheeses. The spring 115 28 is prevented from acting until the warper stop motion operates by means to be now described. Fixed upon the rock shaft 25 is an arm 30, on the upper end of which is pivoted a dog 31 (Fig. 14). 32 and 33 120 are stops to limit the pivotal movement of the dog. The dog normally bears against a stop 34 which is rotatably mounted in the supporting framework. The dog bears against the stop at a point below the axis 125 of rotation of the stop and thus tends to turn the stop. The stop is normally prevented from turning by means of an arm 35 rigidly connected to the stop, one end of which arm bears against a latch 36 pivoted 130

at 37. An arm 38 rigid with the latch 36 normally rests against a stop portion 39 (Fig. 13) on the supporting framework. 5 40 is a bar which is slidably supported at one end in an opening 41 (Fig. 16) in the supporting framework. The bar 40 has a shoulder 42 which is arranged to engage a lug 43 on the latch 36 for the purpose of withdrawing said latch from the arm 35. 10 The bar 40 also has a cam surface 44 which is arranged to ride up on the lower wall of the opening 41 for the purpose of raising the shoulder 42 clear of the lug 43. The opposite end of the bar 40 is connected to 15 one arm of a bell-crank 45 (Fig. 1), the other arm of which bell-crank is connected by means of a rod 46 to an arm 47 which is rigid with the treadle rock shaft S. T is the treadle fixed upon said rock shaft. 20 A weight W carried by an arm W¹ which is fastened on the shaft S tends to turn said shaft in the direction to draw the bar 40 toward the right (Figs. 1 and 13). During the normal operation of the warper, the 25 rock shaft S is held locked by a device such as is ordinarily used in warper stop motions. When one of the drop wires of the warper stop motion falls, said device is actuated to release the rock shaft S, whereupon the 30 weight W turns the shaft S and thereby causes endwise movement of the bar 40 from the position shown in Fig. 16 to that shown in Fig. 13. In the course of the movement of the bar 40, the shoulder 42 engages the 35 lug 43 and thus withdraws the latch 36 from the arm 35. The arm 35 being thus released, the pressure of the dog 31 against the stop 34 causes said stop to rotate out of the path of the dog, thereby permitting the 40 spring 28 to turn the shaft 25 to press the brake plates 19 against the cheeses.

It will be seen that the pressure for braking the cheeses is furnished by the spring 28, the torsion springs 21 constituting yielding means for transmitting such pressure to the cheeses. Being yieldingly connected to the rock shaft 20, the brake plates are enabled to move into contact with all of the cheeses, notwithstanding slight differences 50 in the diameter of the cheeses. The spring 28 contracts until its force is counterbalanced by the pressure of the torsion springs 21 against the cheeses.

At the time the warper stop motion released the rock shaft S, the movement of said shaft also caused the drive belt V to be shifted from the high-speed pulley P to the loose pulley in the usual manner. Simultaneously with the application of the cheese 55 brakes the warp beam B was braked by the means to be now described.

A brake shoe 48 is guided for vertical movement into and out of braking contact with the periphery of the high-speed pulley P. Said shoe is connected to an arm 49

which is fixed on a shaft 50. Fixed on said shaft is an arm 51 to which is connected a tension spring 52. The spring 52 tends to press the brake shoe against the pulley P. The means for normally holding the brake shoe out of action comprises an arm 53 fixed on the shaft 50, which arm carries a pin that normally lies against the upper end wall of a slot 54 formed in the lower end of a link 55. The upper end of said link is pivoted to one arm of a bell-crank 56. The other arm of said bell-crank is connected through a link 57 to a crank arm 58 (Fig. 13) on the shaft 25. It will be seen that when the stop 34 releases the shaft 25 to rotation, the link 55 will be drawn upwardly, thus enabling the spring 52 to apply the shoe 48 to the pulley P.

Referring now to Figs. 13 and 14: when the stop 34 was released through the withdrawal of the latch 36 by the shoulder 42, as hereinbefore described, the pressure of the dog 31 against the stop 34 caused said stop to turn, the arm 35 being swung upwardly against a buffer 59 (Fig. 13). As soon as the dog 31 had passed the stop 34, the arm 35 dropped upon a stop 60. The latch 36 was disengaged from the shoulder 42 through the action of the cam surface 44 in riding up on the lower end wall of the opening 41.

The means for withdrawing the brake plates 19 from the cheeses and for withdrawing the brake shoe 48 from the pulley P comprises a wheel 61 (Figs. 11 and 12) mounted to rotate on an axis parallel with the shaft 25. Said wheel is provided with two diametrically opposite sets of operating devices in order that a half-revolution of the wheel shall suffice to restore the brake mechanism. Each of said sets comprises a roller stud 62 which, in the rotation of the wheel 61 is carried against the arm 30, whereby said arm is lifted. The dog 31 yields to pass the stop 34 when the arm 30 is being raised and rises into position behind said stop to hold the arm 30 in normal position after the roller 62 has passed the arm. The brake plates 19 and the brake shoe 48 are now in normal or inoperative 115 position.

The wheel 61 is driven through a train of reduction gears from a drive pulley 63. Alongside the drive pulley 63 is a loose pulley 64. A drive belt 65 is arranged to be shifted to and from the pulley 63 by means of a shifter fork 66 which is pivoted at 67. A spring 68 acting upon an arm 69 which is rigid with the shifter fork 66 tends to move the shifter fork to throw the drive belt off the tight pulley 63. On the rock-shaft 25 is fixed a cam 70 which is arranged to operate against a projection 71 on the arm 69 to swing the shifter fork to place the drive belt on the tight pulley. 125

When the warper stop motion operates to release the rock-shaft 25, as hereinbefore described, the movement of said shaft in applying the cheese brakes and the beam brake 5 also operates the belt shifter to place the belt upon the pulley 63, whereby the wheel 61 is set in motion.

As the wheel 61 raises the arm 30, the cam 70 is withdrawn from the projection 71 on 10 the arm 69. In order to prevent the spring 68 from shifting the belt 65 to the loose pulley 64 until the wheel 61 has completed its work of raising the arm 30, I provide a lock for the belt shifter, which lock consists 15 of a latch 72 (Fig. 12) which is pivoted at 73 to the supporting framework, said latch having a shoulder arranged to engage an arm 74 that is rigid with the shifter fork 66 and the arm 69. When the shifter fork 66 20 is moved to place the belt upon the tight pulley, the shoulder on the latch 72 drops behind the arm 74 and thus locks the belt shifter. The means for disengaging the latch 72 from the arm 74 comprises two 25 diametrically opposite cams 75 on the wheel 61 (see Fig. 12). After one of the roller studs 62 has raised the arm 30, one of the cams 75 comes into engagement with the projection 76 on the latch 72 and lifts said 30 latch clear of the arm 74, whereupon the spring 68 shifts the belt to the loose pulley.

To prevent the wheel 61 from revolving beyond its proper initial position through momentum after the belt 65 has been shifted 35 to the loose pulley, I provide a brake comprising a brake shoe 77 carried by an arm 78, said arm being pivoted on the axis of the wheel 61. The brake shoe 77 is arranged to engage the periphery of the tight pulley 63. 40 The braking pressure is furnished by a spring 79 which acts upon an arm 80 that is rigid with the arm 78. When the drive belt is being shifted to the tight pulley 63, the brake shoe 77 is removed from said pulley by means of a projection 81 on the shifter fork, said projection engaging and moving the arm 80. When the shifter fork places the belt upon the loose pulley, the projection 81 is removed from the arm 80, 45 whereupon the spring 79 presses the brake shoe 77 against the pulley 63 and stops the rotation of the wheel 61. After the warper stop motion has operated to stop the warper, the operative finds the thread-end on the 50 beam and pieces up the thread. To facilitate the finding of the end on the beam, the operative may set the beam in slow rotation by depressing the treadle T part way. After piecing up the thread, the operative depresses the treadle part way to start the beam slowly and then depresses the treadle 55 fully to throw in the high speed. To prevent any depression of the treadle until the operation of restoring the brake mechanism to its normal position has been completed, I

provide a locking member 82 (Fig. 13), said locking member being pivotally supported at 83 and being arranged to drop by gravity into alignment with the bar 40 and thereby prevent movement of said bar 70 and hence of the treadle T. Rigid with the locking member 82 is an arm 84 which extends into contact with the arm 74. When the belt shifter 66 places the belt 65 on the tight pulley 63, the locking member 82 75 swings by gravity into locking position. When the belt shifter moves the drive belt to the loose pulley 64, the arm 74 operating against the lower end of the arm 84 raises the locking member 82 above the path of 80 the bar 40. After the treadle T has been depressed far enough to set the beam in slow rotation, the beam may be disconnected from the driving power and allowed to come to rest by taking the foot off the treadle. When 85 the beam is thus stopped, the brakes are not automatically applied, as the movement of the bar 40 (Fig. 13) in setting the beam in slow rotation does not cause the shoulder 42 to drop into the horizontal plane of the 90 lug 43.

If desired, the creel may be provided with means for supporting a number of extra cheeses, the yarn from which may be substituted for the yarn from any of the other 95 cheeses. Herein I have shown on each creel frame a stand 85 (Fig. 2), each stand having two spindles 86 which are generally similar to the spindles of the tridents. For each of the extra cheeses there is a brake 19, 100 the brakes on each stand being operated from the adjacent shaft 20 through a connection consisting of crank arms 23^a and rod 24^a (Figs. 3 and 10). The adjacent guide rods 17 are made sufficiently long to 105 guide the strands from the extra cheeses. On the front end of the creel is a horizontal rod 87 to guide said strands to the warper. The rod 87 supports the strands from the extra cheeses above the other strands, and 110 therefore such extra strands may run to any space in the comb on the warper.

As hereinbefore stated, each cheese coasts about the same amount as all the other cheeses at any given stop, the differences in 115 coasting being due to slight differences in the size of the cheeses, as well as in the spring pressure of the brakes and in the friction in the bearings of the various shafts 20. On account of these varying factors it is impossible, with high winding speeds, to make the cheese brakes and the beam brake effective at the same instant. If it were attempted to make the cheese brakes and the beam 120 brake simultaneously effective, the threads 125 of many of the cheeses would be so slack as to cause trouble. I, therefore, make the beam brake somewhat less effective in preventing coasting than the cheese brakes, thereby causing the threads as a rule to be 130

under somewhat greater tension at stopping than when running normally, the differences in the amount of coasting of the various cheeses simply producing differences in the tension of the individual strands.

It will be understood that the invention is not limited to the construction and arrangement herein shown, except as defined in the appended claims.

16 I claim as my invention:

1. A creel-braking mechanism having a brake-controlling lever, thread-controlled means for holding said lever in brake-released position, said lever tending to move into brake-applied position, means for moving said lever into brake-released position, a starting and stopping device controlling said lever-moving means, and means connected to move with the lever for actuating the starting and stopping device.

2. A creel-braking mechanism having a brake-controlling lever, thread-controlled means for holding said lever in brake-released position, said lever tending to move into brake-applied position, means for moving said lever into brake-released position, a starting and stopping device controlling said lever-moving means, means connected to move with the lever for actuating the starting and stopping device, and means for locking the starting and stopping device in starting position.

3. A creel-braking mechanism having a brake-controlling lever, thread-controlled means for holding said lever in brake-released position, said lever tending to move into brake-applied position, means for moving said lever into brake-released position, a starting and stopping device controlling said lever-moving means, means connected to move with the lever for actuating the starting and stopping device, means for locking the starting and stopping device in starting position, and means moving with the lever-moving means for operating the lock to release the starting and stopping means.

4. In a creel-braking apparatus, a brake-controlling lever having an "applied" and a "released" position, thread-controlled means for holding said lever in released position, said lever tending to move into applied position, power means for moving said lever into released position, and means connected to the said thread-controlled means for throwing the power means into operation.

5. In a creel-braking apparatus, a brake-controlling lever having a brake-applied and a brake-released position, thread-controlled means for holding said lever in brake-released position, said lever tending to move into brake-applied position, power means for moving said lever into brake-released position, and means connected to the

said thread-controlled means for throwing the power means into operation.

6. A warping apparatus having, in combination, a creel for rotatably supporting a plurality of cheeses, a brake member for each cheese, each brake member being arranged to bear against the periphery of the yarn mass of the cheese, means for moving the brake members into and out of contact with the yarn masses, beam-rotating means, and a beam brake arranged to permit the beam to supplement the momentum of the cheeses in causing rotation of the cheeses for a time against the action of the brake members.

7. In a creel-braking mechanism, a brake-controlling lever having a brake-applied and a brake-released position, thread-controlled means for holding said lever in brake-released position, said lever tending to move into brake-applied position, and power means for moving said lever into brake-released position.

8. A creel-braking mechanism having brake-restoring means, an operating member, thread-controlled means for moving said member in one direction to set the brake-restoring means in operation, means for moving said member in the opposite direction, and means controlled by the brake-restoring means for locking said member against movement in the last mentioned direction.

9. A creel having a support on which a yarn container may be loosely mounted, a brake member having a convex surface, and means for pressing the convex surface of said member against the middle of the periphery of the yarn mass on a container mounted on said support to stop the container, and for removing said brake member from the yarn mass, the brake member being normally out of contact with the yarn mass.

10. A creel having supports for a plurality of yarn containers, a plurality of movably supported brake members, and means for moving said brake members into and out of contact with the peripheries of the yarn masses on the yarn containers.

11. A creel having supports for a plurality of yarn containers, a plurality of brake members normally out of contact with the yarn masses on the containers, and means for bringing said brake members and the peripheries of the yarn masses on the containers into braking contact with each other.

12. A warping apparatus comprising a creel, beam-rotating means, creel brakes, and a beam brake, the beam brake being less effective to prevent coasting, with relation to the mass controlled, than the creel brakes.

13. A warping apparatus comprising a creel, beam-rotating means, creel brakes,

and a beam brake, the beam brake being so proportioned to the creel brakes that the beam while coasting causes the yarn masses in the creel to revolve after the creel brakes 5 otherwise would have stopped said yarn masses.

In testimony whereof, I hereunto set my hand in the presence of two witnesses.

HOWARD D. COLMAN.

In the presence of—

GEORGE L. CHINDAHL,
MARGARET H. MANN.
